UNITED STATES PATENT OFFICE.

JAMES W. SHIELDS AND ALBERT C. THIELMANN, OF HUBBELL, MICHIGAN.

ORE-CLASSIFIER.

1,073,367.

Specification of Letters Patent. Patented Sept. 16, 1913.

Application filed February 9, 1912. Serial No. 676,665.

To all whom it may concern:

Be it known that we, JAMES W. SHIELDS and ALBERT C. THIELMANN, citizens of the United States, residing at Hubbell, in the 5 county of Houghton and State of Michigan, have invented certain new and useful Improvements in Ore-Classifiers, of which the following is a specification.

This invention relates to ore classifiers 10 and aims to provide a classifier adapted to treat any and all kinds of ore and which may be operated either with or without a head of water.

Another object of the invention is to provide 15 a classifier made up of sections, each including a series or group of independent pockets, the sections being adapted to be disassembled, whereby their number may be increased or decreased as desired, depending 20 upon the character of the ore to be treated.

The classifier embodying the present invention is of that type in which concentration 25 is accomplished by the rise and fall of a body of water, through a screen upon which the bed of ore to be treated has been deposited, and the invention aims to provide means for regulating the depth of this bed 30 of ore, and the invention also contemplates the provision of means for causing a rise 35 and fall of the water in the pockets, which means may be operated either with or without a head of water and may be adjusted to regulate the rise and fall of water in any one or any group of the pockets independently of the others.

The invention aims still further to provide 40 means for supporting the screens upon which the bed of ore to be treated has been deposited in such manner that they will be readily accessible and may be readily removed and cleaned or replaced. Also the invention contemplates so supporting the screens that they may be vertically adjusted 45 within the pockets so that the bed of ore may be supported at the desired height within the pockets.

Another feature of the invention resides 50 in the provision of a continuous trough having oppositely inclined sides, which trough conducts the overflow from each pocket to the next adjacent pocket and from one to the other group of pockets, the inclined walls of the trough serving to retard the flow, thereby allowing the fines to settle and 55 the slimes to overflow.

A further object of the invention is to

provide a novel and highly efficient skimming device for carrying off the scum of metal, which device will not be liable to clog, will continuously perform its skimming function, and will require little if any attention. 60

For a full understanding of the invention reference is to be had to the following description and accompanying drawing, in 65 which:

Figure 1 is a view partly in side elevation and partly in longitudinal section of the classifier embodying the present invention. Fig. 2 is a top plan view thereof. 70 Fig. 3 is a vertical longitudinal sectional view through a portion of the manifold of the classifier. Fig. 4 is a view showing the manifold in end elevation and the classifier proper in vertical transverse section. Fig. 75 5 is a perspective view of one of the boxes of the classifier. Fig. 6 is a perspective view of a box section which may be used in connection with the box shown in Fig. 5 for the purpose of adjusting the screens. 80 Fig. 7 is a perspective view of one of the side plates for holding the box shown in Fig. 5 in place.

Corresponding and like parts are referred to in the following description and indicated 85 in all the views of the accompanying drawing by the same reference characters.

As before stated, the classifier is made up of a number of sections, each including a group of pockets and the manifold of the classifier is also made up of a number of sections, each including a set of plungers 90 and cylinders in which the plungers work, the cylinders being in communication with the said pockets and reciprocation of the 95 plungers in the cylinders serving to cause a rise and fall of the water level in the pockets.

That section in which the material is first treated is indicated in general by the reference character A, the one in which it is next treated is indicated by the reference character B and a third one of the sections is indicated at C and the corresponding sections of the manifold are indicated at D, 100 E and F, respectively.

The body portion of the section A includes a forward wall 1, a rear wall 2, side walls 3 and 4, and a bottom wall 5 and is divided by partitions 6, which extend from the front to the rear wall into pockets 7, 110 8, 9 and 10. The section A also includes a

head 11 which is disposed upon the upper end of the body portion above described and is secured thereto by means of bolts 12 engaged through flanges 13 formed upon the said body portion and head.

By referring to Figs. 1 and 4 of the drawing it will be observed that the front, rear and side walls of the body portion of the section A are formed at their upper edges with an inwardly projecting flange 14 and removably disposed within the head 11 and upon the said flange 14 is a screen 15. For the purpose of holding the screen 15 in place and protecting the walls of the head 11 there is provided a box consisting of a section 16 and a section 17. The assembled edges of the sections of the box are cut diagonally as at 18 and rabbeted as at 19 so as to render the connection between the said ends of the sections substantially water tight, it being understood that by diagonally cutting the edges of the sections, the sections may be readily removed without difficulty by first removing the section 17 and then removing the section 16. Partitions 20 extend from one side wall to the other of the sections 16 and 17 and correspond in location to the partitions 6 within the body portion of the section A. When the box consisting of the sections 16 and 17 is arranged within the head 11, the lower edges of its side and end-walls rest upon the edge portions of the screen 15 and serve to hold these said portions of the screen firmly upon the flange 14. The section 16 of the box shown in Fig. 5, which box is the one arranged within the section A of the classifier, has its side walls and end wall extending upwardly at that end corresponding to the inlet end of the said section A and as indicated by the numeral 21 and these extensions of the said walls of the section 16 constitute the side and end-walls of a housing for the skimming device of the classifier, which device will be presently fully described. This housing is completed by a top wall 22 and a depending inner end-wall 23, the lower edge of which terminates substantially in a horizontal plane with the upper edges of the side and end-walls of the sections 16 and 17. For a purpose to be presently stated, the end-wall of the section 16 and the extended portion thereof is formed with an opening 24. The head 11 of the section A carries a section of the trough of the classifier, the walls of which are indicated by the numeral 25, and as illustrated in Fig. 4 of the drawings, these walls are oppositely inclined. The forward wall 1 of the head 11 is formed with a number of outlet openings 26 which are so arranged that each will drain one of the pockets formed between the partitions 20 and the end-walls of the sections of the box within this head, the corresponding walls of the said sections of the box being formed

with openings 27 which register with openings 26, as shown in Fig. 4.

In order to hold the sections of the box firmly in position, there are provided, within the head 11, two plates 28 which are disposed one against the inner side of the forward wall of the head 11 and the other against the rear wall thereof. Each of these plates at each lower corner is formed with a notch 29 to receive the connecting flanges 30 by means of which the ends of the heads of the adjacent or connected ones of the sections are secured together, as shown in Fig. 1 and these plates are held in place by means of suitable bolts 30' secured through the said walls of the head 11 and through openings 31 in the plates.

By referring to Fig. 4 of the drawings, it will be observed that the lower edges of the plates 28 rest upon the upper edges of the side walls of the sections 16 and 17 of the box and, being bolted firmly in place, serve to hold the said sections of the box against upward displacement. It will also be observed that the upper edges of the plates 30 coincide with the lower edges of the inclined walls 25 of the trough section which is carried by this head.

In order to regulate the depth of material upon the screen within that one of the pockets in the box, which is located between the end-wall of the section 16 and the adjacent partition 20, there is adjustably secured upon the wall 23 of the housing for the skimming device, a plate 31, this plate being held at adjustment by means of bolts 32 secured through slots therein and into the said wall 23. By adjusting the plate, its lower edge may be positioned a greater or less distance above the screen 15 for the purpose stated. Plates 33 which are formed with slots 34, are held in adjusted position on each of the partitions 20 at the end wall of the section 17 of the box by means of bolts 35 secured through the said partitions or the end-wall, as the case may be, and through the said slots 34. It will be understood that by adjusting these plates their upper edges may be positioned at different elevations and that consequently the overflow from one pocket to another can be controlled, they being adjusted to an elevation found to be best suited for the particular ore to be treated.

In connection with the box consisting of the sections 16 and 17, it may be desirable at times to employ an auxiliary box or section which is clearly shown in Fig. 6 of the drawings and the side walls of which are indicated by the numeral 36 and the end-walls by the numeral 37. This box or section is divided at intervals by partitions 38 corresponding in location with the portions 20. When this auxiliary box or section is employed, it is disposed with the lower edges

of its side and end-walls resting upon the flange 14, and the screen 15 is then disposed upon the upper edges of these walls and the upper edges of the partitions 38, after which the box shown in Fig. 5 is set into place and the plates 28 are secured upon the front and rear walls of the head 11. By the provision of the auxiliary box or section shown in Fig. 6, the screen 15 may be supported at different elevations, as will be readily understood. The hutch of each pocket is formed in its bottom with an outlet which is indicated by the numeral 39.

The sections B and C of the classifier are of the same construction as the section A with the exception that their pockets are all of the same capacity and there is no equivalent of the housing for the skimming device and the pockets and other elements of the sections B and C corresponding to like elements of the section A are indicated respectively by the same reference numerals with the addition of the suffixes *b* and *c* respectively.

The manifold D comprises a water-chest 41 which is divided by a number of partitions 42, as is shown in Fig. 3 into compartments 43, 44, 45 and 46, and from each of these compartments leads a pipe 47 connected as at 48 to a pipe 49 which leads from the hutch of the respective pocket of the section A, the compartments 43, 44, 45 and 46 being in this manner placed directly in communication with the hutches of the pockets 7, 8, 9 and 10, respectively. Cylinders 50, 51, 52 and 53 are respectively placed in communication with the compartments 43, 44, 45 and 46 by ports 54 and in each of the cylinders there is mounted for reciprocation a piston or plunger 55. A shaft 56 is journaled in suitable bearings 57 mounted at the ends of the water-chest 41 and upon this shaft there are a number of eccentrics 58 the straps of which are indicated by the numeral 59. One of the eccentrics 58 is located above each of the cylinders and the straps of the eccentrics are connected by means of connecting rods 60 with the respective plungers 55. The sections E and F of the manifold are of the same construction as the section D and the elements thereof correspond to the elements above described as comprising the section D are indicated by the same reference numerals 55 respectively, with the addition of the suffixes *e* and *f*. The shaft 56 may be driven in any desired manner, but preferably from a power-shaft 61 and belt 62.

From the foregoing it will be readily understood that as the plungers 55 reciprocate in the cylinders of the several manifold sections, the level of the material in the pockets of the section A, B and C is caused to rise and fall, resulting in the bed of the material upon the screens of the sections A, B

and C, being first lifted from the screens and then deposited thereon.

The skimmer of the classifier is, as before stated, mounted in one of the compartments of the pocket 11 and comprises a hollow shaft 63 journaled for rotation in a suitable bearing 64 mounted through the opening 24 in the end-wall of the section 16 of the said pocket and this shaft carries, at its inner end, a hollow open-ended dipper head 65 which is curved in the direction of rotation of the hollow shaft and eccentrically to the axis of the said shaft and is in communication with the interior of the shaft at its inner end. This end of the shaft is closed. The dipper head is preferably tapered from its inner to its outer end so as to prevent clogging. The shaft 63 is preferably driven from the power-shaft 61 by means of a belt 66 and the material taken up by the dipper head and conducted through the shaft 63 may be discharged in any suitable receptacle, such for example, as a bucket placed beneath the outer ends of the shaft, as indicated at 67 in Fig. 1 of the drawings. The dipper head 65 is arranged to rotate within the housing formed upon the section 16 of the box shown in Fig. 5, and it will be readily understood that the plate 31 may be adjusted so as to prevent the entrance of gangue into the said compartment or housing.

The operation of the classifier is as follows:—The material to be treated is delivered into the trough of the classifier and flows first into the pocket 7 and upon the screen 15, and as a matter of convenience in describing the operation of the classifier, it will be assumed that all of the pockets of the sections A, B and C have been filled with the material, or in other words, that the pockets have been successively filled and material has overflowed from each pocket into the next adjacent one. Upon downward movement of the plungers 55 of the manifold section D, the level of the material in the pocket 7 will, due to the positive forcing action of the plungers, be caused to rise and the bed of the material upon the screen 15 in this pocket will be momentarily lifted from the screen. Upon upward movement of the respective plunger 55 the level of the material in the pocket 7 will fall, thereby depositing the bed of material upon the screen 15, and this is true of the material in all of the pockets in each of the sections A, B and C. The level of the material in the pocket 7 is of course promptly restored after the plunger has ascended, by reason of the fact that the material is first fed into this pocket, and the other pockets of the first mentioned section are in a like manner promptly supplied with sufficient material to restore the level to normal, by the overflow of material from one

pocket to another, upon the downward movement of the plungers. During the operation of the classifier, the coarser gangue is drawn off from each pocket through the 5 respective outlet plug 26 and the finer gangue will overflow from each pocket into the next adjacent pocket and this overflow is general throughout the three sections A, B and C, the final overflow being at the tail 10 end of the trough C.

As before stated, the inclined walls of the trough of the classifier act to retard the overflow from one pocket to another and from one section to another and in this manner 15 the fines are allowed to settle and the slimes to overflow. As the skimmer shaft 63 rotates, the dipper head 65 takes up the scum from the material within the compartment or housing at the end of the box 20 section 16, and this scum flows out through the shaft and into the bucket or other receptacle 67.

From the foregoing it will be readily understood that the eccentrics may be so adjusted as to vary the stroke of the plungers 25 55 and that furthermore they are independently adjustable so that the plungers may be caused to operate in unison or successively, as desired, and in fact the rise and 30 fall of the level of the material in any of the pockets of any section may be regulated independently of that in any other one of the pockets, and it is also to be noted that the water compartments of the several water 35 chests of the several manifolds are out of communication with each other and that consequently the rise and fall of the material in any pocket will not interfere with that in any other pocket. It will also be 40 understood that the sections A, B and C may be disconnected as may also the sections of the manifold and that consequently a greater or less number may be employed as desired, without in any way affecting the 45 operation of the device, except to secure a more perfect treatment of the ore.

Having thus described the invention what is claimed as new is:—

1. In an ore classifier, a classified section 50 divided by partitions into a number of pockets, a box removably fitted within the section and consisting of separable sections having lap-joint connection, the said box being divided by partitions each lying within 55 the plane of one of the first mentioned partitions, the section being provided in one wall with outlet openings and the corresponding wall of the box being provided with openings registering with the first 60 mentioned openings, a screen disposed between the upper edges of the first mentioned partitions and the lower edges of the partitions within the box and dividing the said

pockets, an overflow plate adjustable within the box, and means for creating a rise and 65 fall of the material within the pockets of the section.

2. In an ore classifier, a classifier section divided by partitions into a number of pockets, a box removably fitted within the 70 section and consisting of separable sections, having lap-joint connection, the said box being divided by partitions each lying within the plane of one of the first mentioned partitions, the section being provided in one wall 75 with outlet openings and the corresponding wall of the box being provided with openings registering with the first mentioned openings, a screen disposed between the upper edges of the first mentioned partitions 80 and the lower edges of the partitions within the box and dividing the said pockets, an overflow plate adjustable upon each of the partitions within the box, one of the sections of the box at one end being increased 85 in height and having transversely extending walls forming a downwardly presented skimming compartment, a skimmer arranged to operate in said compartment, and means for creating a rise and fall of the 90 material within the pockets of the section.

3. In an ore classifier, a series of independent pockets arranged to overflow one into another, a screen dividing each pocket, a trough extending at the upper ends of the 95 pockets and having oppositely inclined walls, and means for creating a rise and fall of the level of the material in the pockets, the inclined walls of the trough extending over the series of pockets in the planes of 100 the overflow from pocket to pocket and serving to retard the overflow from one pocket to the other upon the rise of the material in the pockets.

4. In an ore classifier, a series of independent pockets arranged to overflow one into another, a screen dividing each pocket, a trough extending at the upper ends of the pockets and having oppositely inclined walls, means for creating a rise and fall of 110 the level of the material in the pockets, the inclined walls of the trough extending over the series of pockets in the planes of the overflow from pocket to pocket and serving to retard the overflow of the material from 115 one pocket to another upon the rise of the material in the pockets, and means for regulating the overflow of material from one pocket into another.

In testimony whereof we affix our signatures in presence of two witnesses.
